SABER SAW

Melvin H. Boldt, Glenview, Ill., assignor to G. W.
Murphy Industries, Inc., Houston, Tex.

Filed Jan. 20, 1971, Ser. No. 108,256

Term of patent 14 years

Int. Cl. D8—03

U.S. Cl. D8—64

Fig. - 1

Fig. - 2

FIG-3FIG-4FIG-5

FIG. 1 is a top plan view of a saber saw, showing my new design;

FIG. 2 is a left side elevational view of the saber saw illustrated in FIG. 1;

FIG. 3 is a front elevational view of the saber saw illustrated in FIG. 1;

FIG. 4 is a rear elevational view of the saber saw illustrated in FIG. 1; and

FIG. 5 is a bottom plan view of the saber saw illustrated in FIG. 1.

I claim:

The ornamental design for a saber saw, as shown and described.
